UNITED STATES PATENT OFFICE

FRANCIS BREEDEN, OF BIRMINGHAM, ENGLAND, ASSIGNOR TO AUTOMATIC MOULDING MACHINES LIMITED, OF BIRMINGHAM, ENGLAND

TAMPING DEVICE FOR USE IN MOLDING OPERATIONS

Original application filed February 3, 1928, Serial No. 251,613, and in Great Britain February 8, 1927.

Divided and this application filed March 21, 1929. Serial No. 348,891.

This invention has reference to improvements in or relating to tamping devices for use in molding operations and is concerned more particularly with tamping devices especially suited for use in conjunction with the machinery to be employed in making molds for casting metal described and claimed in my divisional patent application Serial Number 251,613, filed February 3rd, 1928.

10 The invention consists of an improved tamping device for use in molding operations and comprises a frame, a plurality of tamping tools for effecting the consolidation of the sand fed on to the pattern said tamping tools 15 being mounted for reciprocation within the frame, means for effecting a positive lifting of the tamping tools at intermittent periods the tamping tools being capable of a limited free rising and falling motion independently 20 of the said lifting means.

The invention will now be described with particular reference to the accompanying sheet of drawings, wherein:—

Figure 1 is a part sectional side elevation 25 of a portion of the molding machine described in the specification of my aforesaid divisional patent application and shewing two sets of tamping means embodied therewith.

Figure 2 is an end elevation of the tamping means seen in Figure 1 together with the adjacent portions of the molding machine.

As illustrated in the drawings the ramming or tamping devices consist of a plurality of vertically disposed spindles 16^c which pass 35 and work through coincident holes in pairs of horizontal guide bars 16^d extending transversely across the machine. The bars 16^d are connected by side members 16^e which form therewith a frame-like structure, the said 40 side bars 16^e being grooved to engage with vertical guide bars 9^d carried by the framing 9 of the machine as is best seen in Figure 2.

The frame-like structures constituted by the bars 16^d and 16^e are adapted to have a 45 rising and falling motion communicated to them by the action of tappet wheels 35 or like devices mounted on spindles 35^a crossing the upper end of the framing 9. The spindles 35^a are rotated continuously through belt or 50 other gearing. The aforesaid tappet wheels

are located so as to contact with projections 16^f which are preferably in the form of rollers and which are carried by upwardly extending rods secured to the frame-like structures.

55 The spindles 16^c of the ramming or tamping tools are weighted at their upper ends and are provided with fixed collars 16^h adapted to bear normally against the upper side or face of the lower transverse bar 16^d of the frame-like structure. Thus while the spindles are raised by the said frame on its upward motion, the said spindles and tools carried thereby in their descent can, on contact with the sand, rise relatively to the guide 60 frame and subsequently make their percussive blows free from restraint by the guide frame.

65 Normally the frame-like structures and the tamping tools carried thereby are retained in a raised and non-acting position by the engagement below the frame members of a projecting arm 36 carried by a swivelling rod or member 36^a suitably mounted on the framing 9 of the machine adjacent each tool carrying frame, the said rod having thereon a second projecting arm 36^b which extends into the path of a side projection 13^c on the carriage 13. It will be understood that as the carriage passes below each tamping device 70 in succession the action of the part 13^c on the projection 36^b on the respective rods 36^a will turn the arms 36 thereof out of the supporting or retaining position the frames being then permitted to rise and fall under the 75 action of the tappets. The turning motion of the rod 36^a is effected against the action of a spring (not shewn) which serves to return the rod to the normal position in which its arm 36 supports the frame structure after 80 the carriage in its forward motion has passed the projection 36^b.

85 The lower or acting ends of the series of tools may be given any suitable shape a hemispherical shape being found effective in practice and the said acting ends may conveniently be constituted by resilient sponge rubber balls 16^k the said balls 16^k being secured in inverted cup-like sockets 16^m provided on the lower 90 ends of the spindles 16^c but the said acting 95 ends of the spindles 16^c but the said acting 100

ends may, if desired, be of metal or other suitable material.

The tamping tool which operates after the flask or half mold has passed below the third or last sand hopper may, if desired, be a single tool having a width approximately equal to or but slightly less than the internal width of the flask said tool being mounted in a guide frame adapted for reciprocation in the manner hereinbefore referred to with reference to the tools 16^e.

Claims:

1. A tamping device for use in molding operations comprising a base, a support for the molding box and pattern plate, a pair of standards supported from said base, guideways, formed in said standard, a rectangular frame slidably mounted in said guideways, aligned bearings formed in the upper and lower transverse bars of the frame, vertically disposed tamping tools slidably mounted within said bearings, means for permitting of a limited free rising and falling motion of the tamping tools relatively to the frame and means for effecting a positive lifting at intermittent periods of the frame and tamping tools carried thereby said frame, subsequent to a lifting operation, being permitted to fall under the action of gravity to allow the tamping tools to effect the consolidation of the sand in the molding box.

2. A tamping device for use in molding operations comprising a base, a support for the molding box and pattern plate, a pair of standards supported from said base, guideways formed in said standards, an open rectangular frame slidably mounted within said guideways, aligned bearings formed in the upper and lower transverse bars of the frame, vertically disposed rods slidably mounted within said frame, tamping heads fixed to the lower ends of said rods, means for permitting of a limited free rising and falling motion of the spindles relatively to the frame whereby the tamping heads can adjust themselves relatively to the contour of the pattern and means for effecting a positive lifting at intermittent periods of the frame and tamping tools carried thereby said frame subsequent to a lifting operation being capable of falling under the action of gravity to allow the tamping tools to effect the consolidation of the sand in the molding box.

3. A tamping device for use in molding operations comprising a base, a support for the molding box and pattern plate, a pair of standards supported from the base, guideways formed in said standards, an open rectangular frame slidably mounted in the guideways, aligned bearings formed in the upper and lower transverse bars of the frame, vertically disposed rods slidably mounted within the said bearings, tamping heads secured to the lower ends of said rods, means for permitting of a limited free rising and falling

motion of the rods relatively to the frame so as to admit of the tamping heads conforming automatically to the contour of the pattern, a projection carried by said frame, a rotatable tappet wheel adapted to come into contact with the said projection at intermittent periods for effecting a lifting of the frame and tamping tools carried thereby and means for effecting a rotation of the tappet wheel, the frame and tamping tools, subsequent to a lifting operation, being adapted to fall under the action of gravity whereby the tamping heads are enabled to effect the consolidation of the sand in the molding box.

In testimony whereof, I have signed my name to this specification.

FRANCIS BREEDEN.
